UNITED STATES PATENT OFFICE

WILLIAM FREDERICK BOYCE, OF TORONTO, ONTARIO, CANADA

VALVE FOR INTERNAL COMBUSTION ENGINES

Application filed June 10, 1932, Serial No. 616,429, and in Canada May 12, 1932.

The invention appertains in particular to valves for internal combustion engines and essentially concerns a hollow cylindrical valve reciprocably disposed in an engine to control its ports. In this type of valve there is a passage for the gases that is brought into communication with a port or ports by longitudinal movement of the valve imparted to it by crank mechanism. This valve while possessed of certain salutary features over other types, nevertheless has the objection that pressure on the valve top due to explosions or firing is transmitted to the crank mechanism that operates it. Furthermore the burning gases are inclined to attack the upper space between the wall of the valve and the wall of the bore in which it slides. The gases destroy the lubrication and cause carbon deposits on the bearing surface which lessens the engine's efficiency.

According to the present invention it is proposed to provide an annular shoulder which not only relieves the crank mechanism by taking the impact of the explosion but also seals off the bearing surface of the valve at the time of each explosion, i. e., when the valve is closed. This materially increases the efficiency of the valve without appreciably adding to its cost of manufacture.

Referring to the accompanying drawing, Figure 1 is a vertical sectional view through the cylinder of an internal combustion engine showing the invention applied thereto.

Figure 2 is a longitudinal sectional view through the valve.

In the drawing the reference numeral 3 generally denotes the usual cylinder of an internal combustion engine. The cylinder may be of conventional character and of single or multiple bore. It may be water cooled as shown or air cooled according to the design of engine.

The bore 4 accommodates the piston 5 which has the usual rings 6 and is connected to the rod 7 of the crankshaft. The crankshaft is not shown since it does not form a part of the present invention.

In performing this invention there is provided a hollow cylindrical valve 8 reciprocably disposed in the bore 9 and actuated by a

crank mechanism diagrammatically indicated at 10. The crank mechanism is connected to the valve by means of the boss 11 at the lower end 12, which boss is pierced to receive a pin or the like.

The valve is chambered at 13, the chamber of which extends longitudinally for nearly the entire length of the valve. An opening 14 communicates with the lower end of the chamber, while a plurality of circumposed openings 15 communicate with the upper end of the same. The lower opening forms an ingress for the gaseous mixture and the upper openings constitute an egress when the valve is employed as an intake for the explosive mixture.

When the valve is raised the ingress is in register with the port 16, and the upper openings communicate with the head space 17 of the cylinder. In this manner an admixture of gases is admitted to the cylinder head. Conversely, the exhaust valve would operate to discharge the gases.

An annular shoulder 18 is provided at the top of the valve and has a face 19 that seats on the face 20 of the cylinder in the closed position of the valve. The shoulder seals off the entrance to the bearing surface 21 of the valve to preclude gases adversely affecting the same. Additionally the shoulder takes the pressure of the explosion off the crank mechanism, and for this purpose need not be located at the upper end of the valve.

What I claim is:—

In a valve structure of the class described, an engine cylinder having a valve bore communicating with the head space and a port communicating with the bore, a cylindrical valve reciprocably disposed in said bore, said valve being chambered longitudinally and having openings at each end of its chamber communicating with its cylindrical surface, and an annular shoulder at the top of the valve for seating against a surface of the head space to seal off the bearing surface of the valve therefrom.

Signed at Toronto, Ontario, Canada, this 1st day of June, 1932.

WILLIAM FREDERICK BOYCE. 100
